UNITED STATES PATENT OFFICE.

ELMER HARROLD AND CLINTON G. WILDERSON, OF LEETONIA, OHIO.

MOLDING-FLASK.

SPECIFICATION forming part of Letters Patent No. 735,503, dated August 4, 1903.

Application filed April 6, 1903. Serial No. 151,343. (No model.)

To all whom it may concern:

Be it known that we, ELMER HARROLD and CLINTON G. WILDERSON, citizens of the United States, residing at Leetonia, in the county of Columbiana and State of Ohio, have invented certain new and useful Improvements in Molding-Flasks; and we do hereby declare the following to be a full, clear, and exact description of the invention, such as will enable others skilled in the art to which it appertains to make and use the same.

Our invention relates to molding-flasks, and has particular reference to means for alining and maintaining in proper alinement the parts of a sectional flask during the operation of ramming, parting, removing the pattern, and, finally, clamping together the flask-sections preparatory to pouring or casting molten metal.

More particularly stated, the present invention comprises a detachable flask-pin having certain novel characteristics which render it especially efficacious and commercially valuable.

Heretofore the cope and drag of molding-flasks have been alined by the agency of simple cast pintles and corresponding sockets secured to or forming part of the respective flask-sections. These projecting pintles, however, have always been a source of much annoyance in foundries, owing to the great tendency of breakage, especially during the rough handling of shaking out. To overcome this annoyance and loss is, therefore, another object of our present invention, and this is accomplished by the withdrawal of said pins, after the flask-sections have been securely closed, for use in like manner upon succeeding flasks, the one set of pins serving indefinitely.

Heretofore detachable flask-pins have also been used; but it is a further purpose of the present invention to produce an inexpensive one-part pin capable of being readily and most securely interlocked with one flask-section without the intervention of an independent or additional locking member of any description.

The invention will be hereinafter described, and particularly pointed out in the claims following.

In the accompanying drawings, which form

part of this specification, and whereon corresponding letters of reference indicate the same parts in the several figures, Figure 1 represents in perspective a fragment of the cope and the drag of a molding-flask having our present invention affixed thereon. Fig. 2 is a vertical central section through parts illustrated by Fig. 1, the flask-pin, however, appearing in side elevation. Fig. 3 is a top plan view of the invention and of a small portion of the cope to which attached, and Fig. 4 is a detached perspective view of the flask-pin.

Reference being had to the drawings and letters thereon, A B indicate fragments of the cope and drag, respectively, of an ordinary molding-flask, C D metallic plates secured to adjacent edges of such flask-sections, and E F perforated lugs projecting from said plates, as clearly shown by Figs. 1 and 2. The perforation *a* in lug E differs from that in lug F only in the fact that the former is of downwardly-converging form, while the latter is of cylindrical bore, though, if preferred, these perforations may be of any other shape or configuration in cross-section. At the base of lug E the surface of plate C may be recessed slightly, as at *b*, and this is surmounted by an abutment *c*, which projects from and may be cast integral with the surface of said plate.

G represents the detachable and rotatable flask-pin, which may be furnished with an integral angular handle H, as clearly shown, and is provided with an enlarged cam-faced head I, the periphery whereof is slightly mutilated, as at *d*. Beneath its head I, as at *e*, pin G is of converging form to correspond with the convergence of perforation *a* in lug E.

This being a description of our invention in its preferred form of construction, its use and operation may be briefly stated as follows: Pin G is first inserted in perforation *a* of lug E until its converging walls *e* engage those of said perforation *a*, the mutilation *d* in head I permitting passage of abutment *c*. A partial rotation of the pin now by agency of its handle H serves to firmly seats aid pin in taper fit with lug E by the cam action of head I beneath the fixed abutment *c*. The cope of a flask now being placed above the drag in the usual manner, it is quite obvious

that pins G will readily enter the perforations in their respective lugs F, thus guiding and accurately alining the flask-sections ready for reception of patterns and sand. 5 The flask having been properly made up for pouring, it is always customary to clamp the flask-sections firmly together by means of rigid clamps provided for the purpose. When occasion requires, our improved detachable 10 flask-pins are removed by a reverse rotation, whereupon they may be similarly employed in making up succeeding flasks, one set of pins serving a molder for his entire day's work. 15 This being a description of our invention in its preferred form and arrangement, it should be understood that we by no means limit ourselves to this precisely, as many structural changes in the form and arrangement of parts will suggest themselves to the skilled mechanic and may be made without departing from the spirit and scope of our invention. For example, it is not essential that the pin G should be a taper pin. The 20 depression b might be made slightly deeper to serve as a fixed abutment for cam-head I and the abutment c in that event dispensed with, or obviously the handle H might be a detachable handle in the nature of a wrench 25 or wrench-pin. 30 Having thus described our invention, what we now claim, and desire to secure by Letters Patent, is—

1. In a molding-flask the combination with 35 perforated lugs secured to the cope and drag sections respectively, of a detachable flask-pin in taper fit with one of said lugs and loose fit with the other of said lugs, substantially as described.
2. In a molding-flask the combination with 40 perforated lugs secured to the cope and drag sections respectively, of a detachable flask-pin in taper fit with one of said lugs and loose fit with the other of said lugs, and a cam for 45 forcing said pin into the tapering seat, substantially as described.
3. In a molding-flask the combination with

perforated lugs secured to the cope and drag sections respectively, of a detachable flask-pin in taper fit with one of said lugs and loose fit with the other of said lugs, a fixed abutment upon one of the flask-sections, and a cam interposed between said abutment and the pin aforesaid for forcing the latter into its tapering seat, substantially as described. 55

4. In a molding-flask the combination with 60 perforated lugs secured to the cope and drag sections respectively, of a detachable flask-pin in taper fit with one of said lugs and loose fit with the other of said lugs, a fixed abutment upon one of the flask-sections, and a cam integral with the pin aforesaid for coacting with said abutment to force the pin into the tapering seat, substantially as described.

5. In a molding-flask the combination with 65 perforated lugs secured to the cope and drag sections respectively, of a detachable flask-pin in taper fit with one of said lugs and loose fit with the other of said lugs, a fixed abutment upon one of the flask-sections, a cam-head upon the pin aforesaid for coacting with said abutment to force the pin into its tapering seat, and a gate in the cam-head to permit passage of the abutment aforesaid, substantially as described. 75

6. In a molding-flask the combination with 80 perforated lugs secured to the cope and drag sections respectively, of a detachable flask-pin in taper fit with one of said lugs and loose fit with the other of said lugs, a fixed abutment upon one of the flask-sections, a horizontally-actuated cam upon the pin aforesaid for coacting with said abutment to force the pin into its tapering seat, and a suitable handle projecting from the cam as a means 85 of rotating same, substantially as described.

In testimony whereof we subscribe our signatures in presence of two witnesses.

ELMER HARROLD.
CLINTON G. WILDERSON.
